UNITED STATES PATENT OFFICE.

CARL ROTH, OF ZEHLENDORF, NEAR BERLIN, GERMANY.

BALANCING MEANS FOR TURBINES.

954,212.

Specification of Letters Patent.

Patented Apr. 5, 1910.

Application filed September 29, 1908. Serial No. 455,366.

To all whom it may concern:

Be it known that I, CARL ROTH, a citizen of the Confederation of Switzerland, and resident of 9 Annastrasse, Zehlendorf, near 5 Berlin, German Empire, have invented certain new and useful Improvements in Balancing Means for Turbines, of which the following is a specification.

This invention relates to the balancing of 10 turbines used for driving a propeller or like shaft subjected to an end thrust.

The invention is applicable either to turbines of the "overpressure" type such as the Parsons turbine, in which the steam expands and the pressure falls in the moving blades, or to turbines of the "pressure"-type in which the steam is expanded in fixed blades and the moving blades utilize the 15 velocity energy of the steam, or to the "velocity"-type, where the steam is expanded in nozzles, and the velocity energy of the steam is extracted in one or several steps; when several speed-steps are employed, 20 guide-blades are placed between successive steps which merely serve the purpose of 25 changing the direction of flow of the steam.

The specific kind of simple or mixed turbine to which the present invention relates, 30 is that in which a single labyrinth packing is employed and is located at the high pressure end of the turbine and in which the packing is only subjected to a part of the total pressure fall of the steam in the turbine. According to the present invention 35 no balancing surfaces are provided on the exterior of the turbine drum, but the interior of said drum is closed off by a disk subjected on one side to the pressure at an intermediate point in the expansion of the 40 steam situated later than the overload supply inlet, while the interior of the turbine drum on the other side of said disk is subjected to a low pressure. The labyrinth-packing which is arranged on the opposite 45 side of the steam inlet to the blading on the turbine drum and casing, only takes the pressure difference between the pressure of the entrance steam or steam after it has been expanded through nozzles and the pressure of the intermediate point. The remaining 50 pressure fall in the turbine is utilized to exert a pressure on the closed disk against the end pressure on the propeller shaft. By omitting all balancing surfaces on the exterior of the drum the balancing of the pro-

peller thrust is considerably simplified. The end thrust on the propeller varies of course with the load, as also does the pressure fall used for end balancing, so that automatic control of the end balancing is 60 obtained. In addition to the end pressure on the turbine blades the only two factors entering into the calculation for the end balancing are the diameter of the disk subjected to the pressure difference, and the amount of 65 the pressure difference. Since the diameter of the disk is determined by the diameter of the turbine drum there only remains the determination of the intermediate point in the expansion of the steam with which the 70 interior of the turbine drum on the high pressure side of the disk is to be connected.

Referring now to the accompanying drawings, which diagrammatically illustrate this invention, Figure 1 is a diagrammatic cross section of the upper half of a turbine, according to this invention, Fig. 2 is a section through the high pressure end of a turbine showing a slightly modified form, Fig. 3 is a section similar to Fig. 1 showing the invention applied to a turbine with a forward and reversing part arranged in the same casing.

According to the form shown in Fig. 1 the turbine or propeller shaft *a* is supported in the casing *b* at both ends and carries at the high pressure end an open disk or radiating arms *c* on which the drum *d* is supported. The drum *d* is provided at the high pressure end with a labyrinth-packing *e* and the low pressure end of the turbine drum is connected to the shaft by a closed disk *f*. The casing *b* is provided with an inlet *g* arranged in front of the labyrinth packing *e* and blading *h* is arranged on the turbine drum and casing on the opposite side of said inlet to that at which the labyrinth packing is arranged. A further inlet *m* for steam supply during overloading is provided in the casing and beyond this inlet a connection *j* is provided from the blading to the interior of the drum. The connection *j* is therefore arranged later in the expansion of the steam than the inlet *m*. The blading *h* on the drum is continued to the exhaust *k* and the right-hand-side of the disk *f* is exposed to the pressure of the exhaust steam. It will be seen that with this arrangement the drum is of constant diameter throughout its 110

length and no end balancing faces are provided on the exterior of the drum. The shaft a is continued outside the casing and carries the propeller n . The direction of the 5 thrust on the propeller is that shown by the arrow r in Fig. 1 while the direction of the pressure on the turbine blades and also on the closed disk m is that of the arrow r' in Fig. 1. When the end pressure on the 10 propeller shaft varies, the load on the turbine also varies and in consequence the pressure of steam passing through the opening j alters.

As shown in Fig. 2 the turbine may be 15 arranged as a mixed turbine by arranging the high pressure part as a velocity type of turbine. The velocity steps o receive steam from suitable nozzles and this steam then passes through the blading h' . The turbine drum is provided with an opening j' .

In Fig. 3 the turbine casing a^2 is arranged to surround not only the forward turbine drum d' but also the astern turbine p . Between the astern turbine and the forward turbine within the drum there is arranged a closing disk q . The forward turbine drum is provided with an opening j^2 and the astern turbine drum with an opening j^3 through which steam passes from an 20 intermediate point in the expansion of the steam in the turbine. When going ahead at lower speeds steam enters through the opening g^2 and for higher speeds steam enters through the openings g^2 and n^2 . 25 When going astern steam is supplied through the inlet s . Exhaust takes place 30 in both cases through the opening k' . It will be seen that when the forward or reversing turbine is working, the other tur-

bine is running idle in the condenser 40 vacuum.

I claim:—

1. In combination, a propeller shaft, a turbine drum on said shaft, a casing around 45 said drum, a steam inlet and an exhaust outlet on said casing, blading on said drum and casing on one side of said inlet, a labyrinth packing on said drum and casing on the other side of said inlet, a closed disk within said turbine drum, an overload inlet 50 on said casing, a connection from an intermediate point later in the expansion of the steam than said overload inlet, and opening to the interior of the drum on one side of 55 said closed disk and on the opposite side of the labyrinth packing to the steam inlet, said disk being on its other side subjected to the pressure of the exhaust.

2. In combination, a propeller shaft, a forward and reversing turbine drum on said 60 shaft, a casing around said forward and reversing drums, steam inlets to said forward and reversing turbines and a common outlet, blading on said drums and casing on 65 one side of said inlets and extending toward the common exhaust, labyrinth packings on said drums on the other sides of said steam inlets, a closed disk between said drums and connections from intermediate points in the blading on said drums to the 70 interiors of said drums, substantially as and for the purpose described.

In witness whereof I have hereunto set my hand in the presence of two witnesses.

CARL ROTH.
